Primary Examiner — John Windmuller*Assistant Examiner* — Steven Czyz(74) *Attorney, Agent, or Firm* — Ladas & Parry LLP(57) **CLAIM**

The ornamental design for a spinning hairbrush, as shown and described.

DESCRIPTION

FIG. 1 is a top perspective view of a spinning hairbrush embodying our new design;

FIG. 2 is a top plan view thereof;

FIG. 3 is a bottom plan view thereof;

FIG. 4 is a left side elevation view thereof, the right side being a mirror image thereof;

FIG. 5 is a front view thereof; and,

FIG. 6 is a rear view thereof.

The broken lines depict portions of the article that form no part of the claimed design.
